FIRE-EXTINGUISHING APPARATUS

Ralph W. Austin, Weymouth, Mass., assignor to Process Engineering, Inc., Somerville, Mass., a corporation of Massachusetts

Application December 13, 1951, Serial No. 261,423

1 Claim. (Cl. 169—31)

This invention relates to fire-extinguishing apparatus. One object of the invention is to provide a novel fire extinguisher of simple, economical construction which may be easily and quickly recharged and which can be placed in operation in a minimum of time.

A further object of the invention is to provide a novel and improved fire extinguisher of the type wherein an extinguishing liquid is expelled from the extinguishing casing by gaseous pressure.

A still further object of the invention is to provide novel and improved mechanism for use in puncturing the seal of a container in which gas under pressure is stored in order to release the gas when it is desired to operate the extinguisher.

With these general objects in view and such others as may hereinafter appear, the invention consists in the fire extinguisher and in the seal-puncturing mechanism hereinafter described and particularly defined in the claim at the end of this specification.

In the drawing illustrating the preferred embodiment of the invention, Fig. 1 is a vertical sectional view illustrating the operative portions of a fire extinguisher embodying the present invention; Fig. 2 is a side elevation with portions broken away illustrating a modified form of the extinguisher illustrated in Fig. 1.

It has been recognized that those extinguishers wherein an extinguishing liquid is expelled from the extinguishing casing in the operation of the extinguisher and which include the well known soda-acid types of extinguishers now on the market require refilling at frequent intervals in order to maintain the extinguishers in most efficient operating condition. This is due to the fact that the gas-producing chemicals, namely the soda and acid, gradually lose their efficiency.

One aspect of the present invention contemplates an extinguisher wherein this disadvantage is overcome. The gas for expelling the extinguishing liquid is in accordance with the present invention stored under pressure within a sealed container operatively supported within the extinguisher casing, and provision is made for piercing the seal of the gas container and effecting the immediate release of the gas within the container so that a rapid gas pressure is built up within the casing to force the extinguishing liquid from the container and to enable it to be directed against the fire. With this construction the extinguisher is maintained in most efficient operation for relatively long periods of time requiring minimum attention and avoiding the necessity of frequent recharges. In addition, when found necessary the sealed gas container may be replaced with minimum effort and minimum time.

The invention also contemplates novel mechanism for piercing the sealed container to release the gas including a puncturing pin and a rubber body within the puncturing pin is molded. The rubber body serves to enable the puncturing pin to be manually or otherwise depressed into puncturing position, and when the pressure is released from the rubber the latter returns the pin to its initial position. This seal-puncturing mechanism may be used

2

with advantage in various other types of extinguishers in addition to the type wherein an extinguishing liquid is to be discharged by the gas pressure released from the gas container.

Referring now to the drawing, which for purposes of illustration shows the different features of the invention as embodied in an extinguisher of the soda-acid type, 10 is the extinguisher casing provided with the usual threaded open-neck portion 12. A cap indicated generally at 14 is provided with threads 16 arranged to engage threads 18 in the neck portion 12 of the casing 10 to permit the cap to be removably screwed on the neck portion 12 to close and seal the upper open end of the casing 10. Provision is made for supporting a normally sealed gas cartridge holding a substantial amount of gas under pressure from the cap 14. In practice, the cartridge may comprise a carbon dioxide cartridge, and provision is also made for operatively supporting the cartridge-piercing mechanism from the cap to the end that the cartridge may be pierced and the gas released to expel the extinguishing liquid whenever it is desired to operate the extinguisher.

As herein shown, the upper portion of the cap is provided with an upstanding portion 20 provided with internal threads as at 22 and an elongated tubular cartridge holder 24 provided with external threads 26 at its upper end is arranged to be screwed into the threaded opening in the upstanding portion 20 of the cap 14. A flanged portion of a cylindrical, resilient rubber plunger 30 is interposed between the upper end of the cartridge holder 24 and the upper end of the upstanding portion 20 of the cap, and the upper end 32 of the plunger 30 is arranged to extend through a hole in the upstanding portion 20 to project above the upper surface thereof, as shown in Fig. 1. The plunger 30 has molded longitudinally within its central portion a metal puncture pin 34 having its lower end sharply pointed. The pin 34 is arranged to extend below the lower end of the plunger 30, and when the parts are in normal position to be disposed slightly above the upper end of the cap constituting the seal of the carbon dioxide cartridge. The latter is provided with a threaded neck portion arranged to screw into the internally threaded portion 28 of the cartridge holder 24 and in the position shown in Fig. 1. The body portion 38 of the cartridge is enlarged to hold a substantial quantity of the carbon dioxide or other gas under pressure. The cartridge 36 may be readily removed from the cartridge holder when it is desired to recharge the extinguisher. In practice, the carbon dioxide cartridge may be purchased in the open market and is sealed by a metal cap 41 having a thin disk 42 designed to be punctured by the pin 34. The cap 41 is further preferably provided with a metering disk 43 welded or otherwise secured therein and by which the carbon dioxide may be metered when the extinguisher is operated.

The portion of the cartridge holder 24 above the upper end of the cartridge is enlarged to form a chamber 50 and channels or openings 54, 56 in the side walls thereof to enable the gas to pass down into the body of the extinguisher casing when the cartridge is pierced by the depression of the puncturing pin 34 by pressure exerted on the upper end of the rubber plunger 30. After the seal 42 has been punctured the resiliency of the rubber serves to return the parts to the position shown in Fig. 1 when the pressure exerted on the plunger has been released. In operation, the gas pressure developed upon the upper surface of the extinguishing liquid 70 within the extinguisher casing 10 serves to expel the liquid through the discharge nozzle 62 which in practice may be provided with the usual hose 64 as illustrated. In the modification shown in Fig. 2 I have illustrated an operating handle 68 by which downward pressure may be con-

veniently exerted upon the upper end of the rubber plunger 30 to effect the depression of the puncturing pin to pierce the metal disk 42. I have also illustrated a tube 72 arranged to extend from within the exit nozzle 62 downwardly to near bottom of the extinguisher to facilitate the complete expulsion of the extinguishing liquid from within the casing 10.

While the present seal-piercing mechanism finds particular use in extinguishers of the type illustrated wherein an extinguishing liquid is expelled from an extinguishing casing, it is recognized that this piercing mechanism is useful in other types of extinguishers wherever it is desired to pierce the seal of a container within which gas under pressure is stored. For example, instead of a liquid extinguishing medium, dry chemicals may be used as the extinguishing medium, such as a mixture of about 90% sodium bicarbonate and the remainder a mixture of zinc and magnesium stearates. The stearates minimize caking of the bicarbonate.

Having thus described the invention, what is claimed 20 is:

A fire extinguisher having an extinguisher casing provided with a relatively large opening in its upper end and a cap normally closing said opening, a gas pressurized cartridge having a threaded neck and a puncturable upper end, means for suspending the cartridge from the underside of the cap member, said means comprising a hollow cartridge holder member provided with a threaded bore in its lower end and into which the

threaded neck of the cartridge is screwed, said cap having an internally threaded boss provided with an opening, the upper end of the cartridge holder being threaded and screwed into said boss, and cartridge puncturing means comprising a resilient cylindrical rubber plunger having a lower portion positioned in and movable within the upper end of said cartridge holder and having a puncturing pin depending therefrom, said plunger being provided with an integral rubber flange disposed between the upper end of said cartridge holder and said boss and with an upper portion projecting above the cap through said opening in said boss, said puncturing pin being normally disposed a short distance above the upper end of the cartridge to be moved into puncturing position when the plunger is manually depressed to compress the plunger and flex said flange.
